UNITED STATES PATENT OFFICE

163,090

PORTABLE BARBECUE

Charles A. Campbell, Shreveport, La.

Application July 18, 1950, Serial No. 11,236

Term of patent 3½ years

(Cl. D81—10)

To all whom it may concern:

Be it known that I, Charles A. Campbell, a citizen of the United States, residing at Shreveport, in the Parish of Caddo and State of Louisiana, have invented a new, original, and ornamental Design for a Portable Barbecue, of which the following is a specification, reference being had to the accompanying drawing, forming part thereof.

The side of the portable barbecue not shown is substantially plain.

I claim:

The ornamental design for a portable barbecue, as shown and described.

CHARLES A. CAMPBELL.
